[57] CLAIM

The ornamental design for a compost retainer, as shown and described.

DESCRIPTION

FIG. 1 is a perspective view of a compost retainer wherein my design is embodied in a compost retainer having apertures formed in its sides, with the lids shown separated;

FIG. 2 is a top view thereof, without the lids;

FIG. 3 is a bottom view thereof, without the lids;

FIG. 4 is a front elevational view thereof showing the lids raised above the retainer;

FIG. 5 is a rear elevational view thereof with the lids omitted;

FIG. 6 is a right side elevational view of FIG. 4 with one of the lids raised;

FIG. 7 is a left side elevational view of FIG. 4 with one of the lids raised; and

FIG. 8 is a perspective view of a compost retainer wherein my design is embodied in a compost retainer similar to that in FIG. 1, but with the apertures omitted.
